[57] CLAIM

The ornamental design for an eyelid accessory or similar article, as shown and described.

DESCRIPTION

FIG. 1 is a perspective view of an eyelid accessory or similar article showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and

FIG. 7 is a right side elevational view thereof.

A characteristic feature of an eyelid accessory according to my design is that the base strand and the leg strands extending away from the base strand are all of constant and equal thickness.

FIG. 7
